UNITED STATES PATENT OFFICE.

HENRY G. MILLINGTON, OF DANNEMORA, NEW YORK.

STOVEPIPE-SNIPS.

959,245.

Specification of Letters Patent. Patented May 24, 1910.

Application filed March 18, 1909. Serial No. 484,095.

To all whom it may concern:

Be it known that I, HENRY G. MILLINGTON, a citizen of the United States, residing at Dannemora, in the county of Clinton, 5 State of New York, have invented certain new and useful Improvements in Stovepipe-Snips; and I do hereby declare the following to be a full, clear, and exact description of the invention, such as will enable others 10 skilled in the art to which it appertains to make and use the same.

The invention relates to shears and more particularly to the class of stove pipe snips.

The primary object of the invention is the 15 provision of snips of this character in which at one of the ends of the blades is provided a spur or point adapted to be inserted in a stove pipe so as to form a suitable opening to permit the blade to enter the body of the 20 stove pipe whereby the latter can be readily and easily cut.

Another object of the invention is the provision of a stove pipe snip in which the blades of which are adapted to interlock so 25 as to readily and quickly sever a stove pipe or tin sheet of material, and means at one end of one of the blades to enable the ready and easy insertion of the other blade in the stove pipe body so that the same can be cut 30 into the desired length.

Another object of the invention is the provision of a pair of snips for cutting stove pipes or tin sheets of material, which is simple in construction, thoroughly efficient in 35 operation, durable, economical and inexpensive in the manufacture.

With these and other objects in view the invention consists in the construction, combination and arrangement of parts as will be 40 hereinafter more fully described in detail, illustrated in the accompanying drawings which disclose the preferred form of embodiment of the invention to enable those skilled in the art to carry the invention into practice, and as brought out in the claim hereunto appended. It is to be understood however that minor changes, modifications and 45 variations may be made such as come properly within the scope of the appended claim 50 without departing from the spirit of the invention.

In the drawings:—Figure 1 is a side elevation of the invention. Fig. 2 is a plan view thereof. Fig. 3 is a sectional view on 55 the line 3—3 looking in the direction of the arrow of Fig. 1. Fig. 4 is a front end view.

Similar reference characters indicate corresponding parts throughout the several views in the drawings.

In the drawings the numerals 5 and 6 60 designate handles each of which is formed with the usual finger opening or loop 7, at one extremity thereof, and the handle 5, is provided with an elongated slot 8, through which passes the handle 6, the latter being pivoted therein by a cross pivot or bolt 9, in the usual manner. The handles 5 and 6 are extended beyond their pivotal point to form cutting jaws 10 and 11, the latter jaw being of rectangular shape in cross section, and formed with a V-shaped groove 12 in its upper face throughout the length thereof, to provide opposed cutting edges 13, and into this groove 12 is received a cutting edge 14, of the jaw 10, which latter is narrow 75 with respect to the jaw 11, and is adapted to work between the cutting edges 13, of the said jaw 11, to coöperate therewith for severing stove pipes or tin sheets of material. The free extremity of the cutting jaw 10, 80 is pointed as at 15, for the purpose as will be hereinafter described.

Formed on the free extremity of the cutting jaw 11, is a pointed spur or projection 16, which is centrally located thereon and the said jaw 11, being blunt at its end to form abutment shoulders 17 at opposite sides of the pointed spur or projection 16. It is obvious the pointed spur or projection 16 projects beyond the pointed extremity 15, 85 of the jaw 10, so that when the snips are in use the said pointed spur or projection 16 is primarily adapted to penetrate the material to be severed so as to initially form a suitable opening to permit the proper insertion of the pointed end 15 of the cutting jaw 10, thus enabling the severance in an 90 easy and ready manner of the material.

Projecting inwardly from the handles 5 and 6 are stop projections or lugs 18, which 100 latter are adapted to abut with each other when the jaws 10, and 11 are moved to a closed position and in this manner the same are prevented from jamming.

It will be noted the V-shaped groove 12, in the jaw 11 is correspondingly shaped with respect to the cutting edge 14, of the other jaw 10, so that the latter will fit snugly in the said groove when the jaws are closed.

From the foregoing description the construction and operation of the invention will 110 be clearly understood without the necessity

of a more extended explanation which has been omitted.

What is claimed is:—

In snips of the class described, a pair of 5 pivotally connected handles, forwardly tapered jaws formed on said handles, one of said jaws being pointed and formed with a beveled cutting edge, the other jaw being provided with a rearwardly inclined central 10 groove correspondingly shaped to the cutting edge and extending only partially the

depth of said jaw to snugly receive the said cutting edge of the other jaw when the jaws have been completely closed, and a spur projecting from the last named jaw beyond the 15 pointed end of the other jaw.

In testimony whereof, I affix my signature, in presence of two witnesses.

HENRY G. MILLINGTON.

Witnesses:

JAMES H. SIGNOR,
JOHN J. FARRINGTON.
